UNITED STATES PATENT OFFICE.

HERMAN H. BARR, OF NORFOLK, VIRGINIA.

DESIGN FOR FINGER RING OR SIMILAR ARTICLE.

Application filed September 30, 1924. Serial No. 10,927. Term of patent 14 years.

To all whom it may concern:

Be it known that I, HERMAN H. BARR, a citizen of the United States, residing at Norfolk, in the county of Norfolk and State of Virginia, have invented certain new, original, and ornamental Design for Finger Rings or Similar Article, of which the following is a specification.

Figure 1 is an edge view of a ring bearing the new design, and Figure 2 is a side elevation of the same.

I claim:

The ornamental design for finger ring, or similar article as shown.

HERMAN H. BARR.
